UNITED STATES PATENT OFFICE

STEWART F. HETTIG, OF WARRIOR RUN, PENNSYLVANIA

RAIL HANDLING TRUCK

Application filed August 20, 1931. Serial No. 558,354.

This invention relates to a truck primarily adapted for handling of railroad rails.

A particular object is to provide a novel construction wherein the rail carried is so suspended that it serves as the draft means for the truck in combination with a hook or equivalent means to prevent undue lateral or sidewise motion of the rail.

The more specific objects and advantages will become apparent from a consideration of the description following taken in connection with the accompanying drawings illustrating an operative embodiment.

In said drawings:—

Figure 1 is a view of the truck in side elevation,

Figure 2 is a plan view thereof,

Figure 3 is a fragmentary side elevation taken from the opposite side to Figure 1,

Figure 4 is a vertical sectional view taken on the line 4—4 of Figure 2, and

Figure 5 is a vertical sectional view taken on the line 5—5 of Figure 1.

Referring specifically to the drawings, the truck comprises a suitable frame in which a pair of axles 11 are journaled and which carry wheels at 12. The bearings of the frame for said axles 11 are shown at 13 and are preferably in detachable sections bolted together as at 14.

Said frame 10 includes a superstructure 15, mounted by the diagonals 16 in combination with cross braces 17. The superstructure is generally in the form of a hollow rectangular body. Said superstructure has a drum 18 having a shaft 19 journaled therein, equipped at one end with a pawl and ratchet mechanism 20 and at the other end having a gear wheel 21 keyed thereto. Gear wheel 21 meshes with a pinion or smaller gear 22 keyed to a shaft 23 whose opposite end is square as at 24 and adapted to be detachably engaged by an operating crank 25.

A chain or suspending element 26 is connected to the drum 18 and at its lower end has branches 27 connected to the levers 28 of tongs generally designated 29, the levers being pivoted together as at 30.

A stay member or rod 31 is connected to the chain 26 and at its other end is looped as

at 32 and passed through an opening 33 in a suitable part of the frame 10.

The tongs 29 as shown in the drawings, are engageable with a railroad rail generally designated 34 and the crank 25 may be operated to wind the chain 26 on drum 18 and elevate the rail into contact with the under surfaces or substantially so, of the axles 11. Due to the provision of member 31, this single supporting means for the rail is sufficient because the member 31 by preventing the chain from twisting will prevent undue lateral swinging movement of the rail, causing it to practically continuously remain parallel to the wheels as shown in the drawings. Furthermore because the rod 31 connects the chain, adjacent to the tongs 28, with the frame, it will be apparent that it serves also as a tractive means so that the rail itself may be utilized as the draft means, to which end a clevis 35 is adapted to be secured thereto by a bolt 36 passed through openings normally used in the securing of the fish plate thereto. The draft power may be connected to the clevis 35 in any desired manner.

Various changes may be resorted to provided they fall within the spirit and scope of the invention.

I claim as my invention:—

1. A railroad truck comprising a frame, wheels on the frame, means on the frame to elevate the rail and maintain it substantially parallel to the wheels and above the ground line, whereby the rail may serve as a draft means, and means to prevent twisting movement of said elevating means and accordingly of the rail, said means connecting the elevating means and frame to provide traction means therebetween.

2. A railroad truck comprising a frame, wheels on the frame, a superstructure, a rotatable drum carried by the superstructure, a flexible element suspended by the drum, means on the flexible element engageable with a rail to suspend the same, and means connecting said element and the frame preventing twisting of the element to maintain the rail substantially parallel with the wheels and providing tractive means connecting the

element and frame so that the rail may be used as a draft means.

3. A railroad truck comprising a frame, wheels on the frame, a superstructure, a rotatable drum carried by the superstructure, a flexible element suspended by the drum, means on the flexible element engageable with a rail to suspend the same and maintain the rail substantially parallel with the wheels so that the rail may be used as a draft means, and a rod engaging the frame and flexible element preventing twisting movement of said element and providing tractive means connecting the flexible element and the frame.

4. A railroad truck comprising a frame, wheels on the frame, a superstructure, a rotatable drum carried by the superstructure, a flexible element suspended by the drum, means on the flexible element engageable with a rail to suspend the same, and a rod engaging the frame and flexible element preventing twisting movement of said element and providing tractive means connecting the flexible element and the frame.

In testimony whereof I affix my signature.
STEWART F. HETTIG.
